UNITED STATES PATENT OFFICE.

CHARLES J. GUTBERLET, OF PHILADELPHIA, PENNSYLVANIA.

TELEPHONE-RECORD TICKET PACK.

Application filed December 17, 1925. Serial No. 76,046.

The present device meets the very specialized requirements of telephone switchboard station operation, and its novelty consists in the means employed to meet these requirements. In the management of these stations where tolls are collected, a very rapid identification of the call both by the telephone number of the caller and the called must be made by the operator and noted by her, and the name of the caller especially and information concerning the call must be made into a semi-permanent record, much of which business reasons, and in some localities legal reasons as well, require shall be kept confidential from even the most of the employees of the company, who would have casual access to these records, and even be used to do minor things with reference to them. These records should be in a form that is easily produced without copying, and they must be filable and the files be kept easily up to date, and the records be removable and separable in some cases. This has resulted before my invention in the use of ticket systems in various forms, and my ticket pack is an improvement by which the requirements of switchboard accounting are more readily and completely secured than heretofore.

Fig. 1 is a face view of one of the two tickets of the pack; and Fig. 2 is a face view of the other ticket. Fig. 3 is a face view of the pack in a position for semi-confidential filing; Fig. 4 is a side elevation of several packs with a subscriber's folder; Fig. 5 is a face view of the pack arranged for full confidential filing and Fig. 6 is a side elevation of a stack of unfilled-in tickets.

Tickets of this kind have to come packed so that they can be removed individually from the stack quickly and certainly by the operator, who must not be obliged to give any attention to them except to reach to the stack. The folded-over-end form of ticket best serves this purpose because enough spring will always exist in the tickets to separate the ticket at the end of the pack from those below it. A stack of tickets is shown in Fig. 6.

The two tickets that form the pack are made to work together to meet these requirements. The report ticket the face of which is shown when the flap 2 is folded out on a level with the body 1, shown in Fig. 1 has the line of folding shown by the

dash and dot line 7, and has below the third heavy line 6 the blanks for the more confidential information so that when the flap 2 is folded upward, it will cover all below that line. As the tendency of the ticket is to take this position, the more confidential information is normally covered. These tickets when filled out are usually stacked and dispatched to the audit room by messengers who cannot readily pry into the contents of the stacks, especially the information under the folded-over part, 2. This ticket contains the fuller details of the call, on the normally exposed portion between the top and line 6, and also a large space for confidential remarks, in the space usually covered by the flap, and also under this space the names or numbers of the persons concerned in making the connection or record or both. This ticket is usually sufficient to justify its use as above described.

However, it is not usually sufficient protection to allow its use in filing; where my complete device employing both tickets in a pack is used. In Fig. 2 is shown the face of another ticket having the body 3 and the flap 4 normally folded over on the dash and dot line 9 so that the body 3 and the flap 4, are substantially each of the same length as the ticket shown in Fig. 1. This ticket has its face quite different from the face of the ticket shown in Fig. 1. The names of the sender and receiver are omitted and only the telephone numbers are given and when the flap 4 is turned up, the edge of the flap reaches the heavy line 10 and covers everything except the sender's telephone number and place and such marks as may be placed in the spaces above "from". The lower space on the ticket has spaces for entries under cypher notation and some information not particularly important. This ticket can be sent rather freely by messenger. However, its really important use is in connection with the "report" ticket, as shown in Figs. 4 and 5 especially. By placing the back of the body 3 on the face of the body 1, with the flap 4 covered by the flap 2, in an ordinary card filing box or other suitable filing receptacle, the confidential portions are securely protected from examination by a person sent to the files to fetch a particular item, especially so, if the faces were pinned together by a pin 12, or otherwise removably fastened together. These tickets are packed tight

enough in filing to prevent the examination of the matter under the flaps without removing the filed papers. It is obvious a person could be sent to fetch a particular pack and 5 permitted to get them from the files without such person being able to get any information beyond the number of the telephone sending a call, as that is all that would ordinarily project above the top of the filing box, 10 and the bulk of the folded-over flaps and backs, being greater than the upper part of the back alone, permitting the lower part of the tickets to be packed tightly yet leaving the upper parts to be pressed apart to 15 search for the telephone numbers of the senders. When a pack having the number of the telephone of the sender has been located, should it be required to identify the pack by the place called or the telephone 20 number of the receiver, a very slight lift of the pack of two tickets will enable these to be seen as both lie on the face of the body, 3, just below the upper edges of the upturned flaps. But this slight lifting will 25 not be sufficient to disclose anything more on either ticket. No file messenger need do more than this under any circumstances. If the file messenger endeavored to pry into the files therefore, he would be sure of detection in a very short time. The two 30 tickets can lie together as shown in Fig. 3, when on the auditor's or executive's desk without undue publicity while very readily accessible to him to gain all the information

contained in them without risk of the two 35 tickets becoming separated.

I claim:

A ticket pack consisting of a pair of tickets of substantially the same shape and size, each folded at substantially the same 40 distance from the top into a body portion and a flap, the flap of each ticket folding over a portion only of the body of each ticket and covering and hiding the face of the lower portion of said body, the lower 45 portion of each of these tickets where the said face would be covered by the flap, containing appropriately designated spaces for confidential information, each of said pair of tickets containing different printed matter from the other, and the said tickets being packed in pairs, each pair consisting of one ticket of each kind, both folding the same way and the flaps lying in the same 50 direction one inside the other with the body and flap of one enclosing the body and flap of the other, the inner ticket having on the upper part of its face an appropriately designated space for the telephone number of the sender and upon the part covered by the flaps an approximately designated space 55 for the number of the receiving telephone, and covering and concealing all matter on the face of the enclosing ticket and all matter on the enclosed ticket above the turned up flaps being concealed thereby, said bodies of said tickets being pinned together.

CHARLES J. GUTBERLET.
